THERMOSTATIC SWITCH

Ralph M. Manning, West Medford, Mass., assignor to General Electric Company, a corporation of New York

Application October 24, 1950, Serial No. 191,858

3 Claims. (Cl. 200—139)

1

This invention relates to condition responsive switches, and particularly to room thermostats such as are used for energizing the electrical control circuits in domestic heating and air conditioning installations, although certain of the improvements of the present invention may be useful in other types of condition responsive control devices.

The object of my invention is to provide an improved thermostat which is simple and rugged in construction, reliable in operation, inexpensive to manufacture, and easy to install and maintain, and which provides simple calibration means for use by the consumer in addition to providing for factory calibration.

In carrying out my invention in a preferred embodiment thereof, I provide a flatly disposed elongated subbase which is made at least partly of insulating material. Joined to the subbase at two points near opposite sides thereof is an elongated base composed of a concatenation of interfitting conductive and insulating members which provides for the mounting near one end of an adjustable dial and cam structure for varying the setting of the thermostat. Near the other end of the base is the switch structure, while at an intermediate point a leaf spring is joined to the base for supporting a flat bimetal thermostatic element which operates the switch in response to temperature changes. A readily detachable cover is provided for the complete mechanism.

For a clear and more complete understanding of the invention, reference should be had to the accompanying drawing in which Fig. 1 is a front plan view of the thermostatic mechanism with the cover in section and portions cut away in order to reveal the operating parts; Fig. 2 is a side elevation view of the mechanism with the cover in section; Fig. 3 is a side sectional view of the thermostatic switch along the line 3—3 of Fig. 1; Fig. 4 is a top view of the mechanism with the cover in section; Fig. 5 is a sectional view along the line 5—5 of Fig. 1; while Fig. 6 is a sectional view along the line 6—6 of Fig. 1.

As shown in the drawing, all of the operating parts of the thermostatic switch which is designated generally by the numeral 10, are mounted in cooperating relation upon a flatly disposed elongated subbase 11 composed of two principal parts. One such principal part is a flatly disposed metal member 12 having a cut-out center portion 13 so that the metal member forms an outline around the device which resembles an irregular picture frame when viewed from the

2

rear. The thermostatic switch is preferably mounted vertically in the position shown in Figs. 1, 2, and 3. At the top, bottom and along both sides, the metal subbase member 12 is provided with right angle portions 14 projecting outwardly from the flat vertical portion. The second principal part of the subbase 11 is a flat rectangular member of insulating material 15 which is secured to metal member 12 by a plurality of horizontal projections 16 on right angle portions 14 along the sides of the subbase; member 15 does not extend the full length of member 12 as will be brought out in more detail subsequently but is positioned so that the upper and lower sides of the rectangle form two transversely disposed horizontal insulating portions intermediate the upper and lower extremities of member 12. Projections 16 are formed integrally with the angle portions 14 along the two sides of the metal subbase member and are bent to the position shown best in Fig. 4 to retain the insulating member 15 in place on metal member 12. Also cooperating in holding insulating member 15 in place are a pair of angle portions 17. Angle portions 17 are formed integrally with member 12 and are connected thereto by sector portions 18. Portions 17 extend along the entire length of the inner side surfaces of insulating member 15 and in cooperation with projections 16 provide a very rigid connection between insulating member 15 and metal member 12 to form a unitary base member 11. The ends of angle portions 17 abutting shoulder portions on insulating member 15 at locations 19 prevent longitudinal movement of insulating member 15 with respect to member 12, while projections 14 in cooperation with projections 17 prevent lateral movement and projections 16 hold the insulating member 15 firmly against the flat portion of metal member 12.

The subbase 11 also includes an offset portion or boss 19 formed integrally with metal member 12 and having a longitudinally elongated screw-receiving opening 20 therein. Near the lower end of the subbase a second boss 21 is provided having a transversely disposed screw-receiving opening 22 therein. Bosses 19 and 21 with their respective openings 20 and 22 are used for securing the subbase 11 to a wall or other mounting surface, the horizontally disposed elongated opening in one projection and the vertically elongated opening in the other providing for the ready positioning and alignment of the subbase 11. The remainder of the thermostatic mechanism and the cover, which are subsequently de-

scribed in detail, are not in position at the time the subbase 11 is installed.

The metal subbase member 12 is preferably formed from a single piece of metal by first punching out suitable openings and then forming the desired angular and offset portions by means of suitable dies. Insulating subbase member 15 is preferably cut from a thin flat sheet of molded insulating material.

The thermostatic mechanism is secured to the subbase 11 by two angular metal members 23 which serve also as terminal members. Each of the members 23 comprises a lower inwardly disposed flat portion 24, an intermediate portion 25 joined at right angles at the outer edge of portion 24, and a second outwardly disposed flat portion 26 joined to portion 25 at the outer edge thereof and positioned substantially parallel to portion 24. One of members 23 can be seen in Fig. 3 of the drawing, a portion of both of them can be seen in part in Fig. 1, but Figs. 4 and 5, perhaps, show these two members most clearly. Each portion 24 of a terminal member 23 has a pair of leg portions 27 projecting at right angles (upwardly in Fig. 5) beyond insulating member 15 on opposite sides of the upper horizontal portion of this member. Recesses are provided in the upper and lower edges of the upper horizontal portion of insulating member 15 to receive the leg portions 27 of terminal members 23 and these terminal members are secured to the base by assembling them on the insulating member 15 and then pinching together the oppositely disposed leg members on each terminal member 23. In addition the two individual legs of each leg portion 27 are spread apart to engage the sides of the recesses in member 15 to further aid in securing terminals 23 to member 15. One of the lower portions 24 of a terminal member 23 is tapped to receive a terminal screw 28, as shown in Figs. 1, 3 and 5, while the hole in the other portion 24, which is labeled 29 in Fig. 1, is not tapped since there is no electrical connection at this point. Screw 28 is provided with a washer 23a, while insulating member 15 is provided with an untapped hole beneath the terminal screw 28 to allow this screw to project through the insulating member as far as is necessary in order to make a mechanically tight electrical connection.

The terminal members 23 jointly support a base which supports the movable elements of the mechanism. This base includes a relatively small conductive member 30 secured to the left-hand (as seen in Fig. 1) terminal member 23 and a relatively large conductive member 31 connected to the righthand terminal member 23. Conductive member 30, as best seen in Fig. 2, includes a first flat portion 32 which is secured to terminal member 23 in a suitable manner such as by a screw 33 engaging a recess in the lower edge thereof, an oblique intermediate portion 34 and a second flat portion 35 offset from and substantially parallel to portion 32. Conductive member 31 includes a flat portion 36 which is coplanar with portion 32 of the other conductive member but is separated electrically therefrom. Portion 36 covers a much larger area than portion 32, the latter extending only along the left side as shown in Fig. 1, while portion 36 as shown in Figs. 1 and 3 completely surrounds a circular cam member 37 which is described in detail subsequently. In addition to portion 36, member 31 includes a first oblique portion 38, a first flat offset portion 39, a second

oblique portion 40, a second flat offset portion 41, and a right angle end portion 42 of reduced width. Member 31 may also be provided with a central groove 87 in one surface along a portion of the length thereof together with a corresponding projecting portion 87a on the opposite surface to provide added strength and rigidity. Member 31 is secured to the righthand terminal member 23 in a suitable manner such as by a screw 125 engaging a recess in the lower edge of portion 36, thus connecting member 31 rigidly to the subbase 11 through right hand terminal 23.

The coplanar conductive portions 32 and 36 jointly support a flat insulating member 43, this member being secured to portion 32 by a pair of rivets 44. Member 43 is secured to portion 36 by a plurality of integrally formed projecting portions 45 on portion 36 extending through corresponding apertures in member 43, each such projection having a divided extremity portion which is spread apart to engage the sides of its corresponding aperture to firmly secure member 43 to member 36. Circular cam member 37, which is preferably of molded resinous insulating material, projects through an opening in portion 36 as previously mentioned, a shoulder portion 48 on cam member 37 engaging portion 36 and providing for the rotation of the cam member relative to portion 36. Insulating member 43 is provided with a larger opening than portion 36 through which the smaller inner end portion of the circular cam member 37 extends, as best seen in Figs. 3 and 5. An insulating spacing member 46 is positioned on the outer surface of portion 36 surrounding an intermediate diameter portion of the cam member 37 while a dial member 47 is positioned abutting the outer surface of spacing member 46, both outer members 46 and 47 being held in frictional engagement with the remainder of the cam assembly by a second shoulder portion 48' on cam member 37.

Cam member 37 has a central opening 49, the inner surface of which forms a helical cam surface 50. At the bottom of opening 49 a smaller opening is provided in which is positioned a member 51. One end of member 51 is provided with a projecting flange portion 52 which engages a corresponding shoulder in the bottom of opening 49, while the other end of member 51 is provided with a reduced diameter shank portion 51' just beyond the inner surface of cam member 37. The entire cam assembly is rotatably secured to portion 36 by a flatly disposed resilient member 53 having an elongated opening 54 therein which is forced over the reduced diameter shank portion 51' of member 51 with the ends of member 53 in engagement with insulating member 43 thereby to hold the cam assembly in position. Member 53 can best be seen in Figs. 3 and 5. Rotatable circular dial member 47 has a knurled portion 55 around the circumference thereof to facilitate rotation of the dial by hand, while indicia 56 are provided on the outer surface of the dial to provide an indication of the setting of the thermostatic switch. The dial 47 is also provided with an arcuate slot 57 subtending an angle of more than 180 degrees of the upper portion of the dial in this typical illustration. Through this slot projects a pointer 58 which cooperates with the indicia on the dial to indicate the setting of the switch. Pointer 58 has a base portion 59 extending along the under surface of the upper portion of insulating member 43, and portion 59 is secured to member 43 by a pair of posts 60

which project through member 43 and up through slot 57 in the dial to provide stops for the dial in cooperation with the end portions 61 of slot 57. In this manner the angle through which dial 47 may be rotated is limited to a predetermined magnitude, such as approximately 180 degrees.

Cam member 37 is rotatable with respect to dial 47 by overcoming the friction between these two members. To aid in rotating one with respect to the other, cam member 37 is provided with an arcuate flange portion 62 of increased diameter around the upper portion of the outer periphery of the outermost surface, and portion 62 is provided with a pair of indentations 63 to facilitate moving member 37 with the finger or by means of a suitable instrument while holding dial 47. The end shoulder portions 64 of flange 62 cooperate with a raised projection 65 on dial member 47 to limit the rotation of member 37 with respect to dial 47.

Provision is made for locking dial 47 comprising a small, flat, rectangular member 66 which is positioned beneath the dial and has a recess 67 near one end which embraces the righthand pin 60. The other end of member 67 is tapped to receive a screw 68 which projects from the front of the dial 47 through the slot 57, the head of the screw engaging the outer surface of the dial. In order to lock the dial it is necessary only to tighten screw 68, while loosening the screw unlocks it again.

Device 10 includes as the operating element a bimetal thermostatic member 69 which is supported centrally of the device by an electrically conductive resilient leaf spring 70 and operating arm 76. Spring 70 in turn is firmly secured to portion 39 of the subbase assembly by a pair of rivets 71 which extend through a plurality of insulating blocks 72, the rivets 71 and the blocks 72 being so constructed and arranged that spring 70 is electrically isolated from portion 39 of electrically conductive member 31. Spring member 70 is preferably provided with outwardly projecting right angle portions 73 which fit in corresponding recesses in the center insulating block 72 to insure that member 70 will be held firmly without movement with respect to the base. Spring 70 is connected electrically along the left side to portion 35 of conductive member 30, this preferably being accomplished by welding a pair of projections 74 on spring 70 to portion 35 along the joint 75.

The upwardly extending metal cantilever supporting arm 76 is secured to spring 70 in a suitable manner such as by a pair of rivets 71. At the upper end of member 76 bimetal element 69 is secured thereto in a suitable manner such as by a pair of screws 126 to form an electrical connection therebetween. The bimetal 76 is slotted where screws 126 pass through it to provide adjustment of the bimetal position. A calibrating screw 78 having a lock nut 79 is also provided near the end of member 76, the inner end of the calibrating screw 78 being biased into continuous engagement with the helical cam surface 50 of cam member 37 by the action of spring 70.

At the lower end of the device 10 there is provided a contact assembly which includes a movable contact 80 mounted on bimetal 69. Two eyelets 127 are used to secure an armature 81 to the end of the bimetal, armature 81 cooperating with a permanent magnet 82 which preferably has a high residual coercive force and is disposed in magnetic attractive relation with the

armature 81 so as to provide a snap action in the engagement and disengagement of the circuit controlling contacts, these contacts including movable contact 80 and a contact 88 having limited travel. Magnet 82 is supported by a non-magnetic member 83 which is secured to portion 41 of the base in a suitable manner such as by a pair of rivets 84, member 83 having a pair of outwardly projecting portions 85 positioned on either side of reduced width angle portion 42 of the base and embracing magnet 82.

The relatively fixed contact 88 which cooperates with movable contact 80 in opening and closing a circuit is mounted on a cantilever spring 15 member 89. Cantilever spring 89 and a second cantilever spring 90 are firmly secured in superimposed relation on the base structure by rivets 71 which connect them electrically to member 31, while insulating blocks 72 isolate them from spring 70. Spring 89 is relatively weak and is biased toward bimetal 69 while spring 90 is relatively strong and is biased in the opposite direction. Spring 90 is provided with a projection 91 which embraces spring 89 and thereby restrains the latter in accordance with the position of spring 90. When the bimetal actuates contact 80 and contacts 80 and 88 close, spring 89 flexes and permits contact 88 to move inwardly a small amount until contact is made by spring 89 with spring 90, the distance of such movement depending upon the location of projection 91 with respect to the flat portion of spring 90. When the bimetal 69 sets up a force tending to open the contacts by pulling the armature 81 away from the attractive zone of magnet 82 in order to open the contacts 80, 88, the described arrangement permits contact 88 to follow contact 80 until spring 89 engages projection 91, after which the contacts part with a snap. This is to prevent chatter of the contacts. If such an arrangement is not used, chatter may result when the switch opens due to the fact that just before the armature pulls free of the magnet the force on the contacts must pass through zero which allows the circuit to break and remake.

The position of spring 90 and hence the relative positions of armature 81 and magnet 82 in the switch closed position are adjusted by a set screw 92. Set screw 92 has external threads engaging corresponding internal threads in an aperture in portion 41, and for the purpose of preventing free movement is also threaded through a resilient projecting angle member 93 which may conveniently be formed integrally with member 83 and is thus secured to the base by rivets 84. An insulating member 94 is secured to set screw 92 by a lock nut 95 cooperating with the head 92a of the set screw. Member 94 is arranged for limited arcuate movement, this member having an opening 96 through which reduced width angular portion 42 of the base projects, the end portions 97 of member 94 adjacent opening 96 providing stops for member 94. As will be discussed in greater detail subsequently, member 94 and set screw 92 are used to adjust the differential of the thermostatic switch. A projection 98 forming a pointer on member 94 is provided for cooperation with indicia 99 to indicate the differential adjustment. Indicia 99 are located on an offset portion 100 of metal subbase member 12 positioned along the outer edge of angular portion 42 along the bottom of member 12.

Provision is made in device 10 for the inclusion of one or two resistors, if desired. To provide a mounting for these resistors, the lower horizontal

portion of insulating subbase member 15 is provided with two additional terminal members 101 which may be identical to the righthand terminal member 23 (see Fig. 1) on the upper horizontal portion of member 15. Each terminal member 101 includes a flatly disposed portion 102 positioned in engagement with member 15, each portion 102 having a pair of oppositely disposed leg portions 103 extending in recesses on opposite sides of member 15 and securing member 101 to member 15 in the same manner as described previously for leg portions 21 of terminal members 23. Each flat portion 102 is provided with a tapped opening in which are positioned screws 104 having washers 104a. Screws 104 project through corresponding untapped openings in member 15 and provide for attaching connecting wires between washers 104a and portions 102. Each terminal member 101 also has an intermediate right angle portion 105 and an offset portion 106 substantially parallel to flat portion 102. Screws 107 and washers 107a cooperating with portions 106 are provided for securing one terminal of each of the resistors, portions 106 being threaded to receive the screws while base 15 is provided with untapped openings 108 corresponding to the locations of screws 107 to provide space for the entry of the screws if necessary. If desired, portions 106 may be provided on their outer surface with depressions 106a to receive the resistor terminal wires.

A pair of resistors 109 and 110, which may be respectively preheat and night set-back resistors, may be connected between terminals 101 and terminals 23, the upper terminal wire 109a of resistor 109 being secured between member 30 and lefthand terminal 23, and the upper terminal wire 110a of resistor 110 being secured between member 31 and righthand terminal member 23, while the lower terminal wires 109b and 110b of the resistors are secured respectively in recesses 106a. It will be understood that upper terminals 23 may also be provided with recesses, similar to recesses 106a in the lower terminals, to facilitate the installation of terminal wires 109a and 110a.

It will be understood also that either or both of resistors 109 and 110 may be omitted, if desired, and connections made directly to terminals 23 instead of to terminals 101 and thence through the resistors to terminals 23. In any event, terminals 23 can be utilized whenever needed whether terminals 101 are utilized or not, and in the normal connection for a night set-back resistor such as resistor 110 it will be necessary to utilize the righthand terminal 23 for one of the external connections for the thermostat.

All of the screws in this device which are used either to fasten the base to the subbase or for external wiring are swaged on the end so that they cannot be readily removed and lost.

The thermostatic switch 10 is provided with a cover which is designated generally by the numeral 111. The cover 111 is specially formed and arranged so that it may be readily mounted and dismounted on the subbase 11 to enclose the thermostatic switch mechanism, with both the manual temperature setting dial 47 and the manual differential adjustment member 94 projecting through the upper and lower ends respectively of the cover for operation externally thereof. A suitable enlarged opening 112 is provided in the upper end of the cover 111 to permit the upper portion of dial 47 to extend therethrough. The

cover 111 also is provided with an enlarged portion 113 which hooks over a projection 114 on an angular portion 14 along the upper edge of metal subbase member 12, portion 113 thus securing the upper edge of the cover. The lower end of the cover is detachably secured to the subbase by a pair of projections 115 which engage a pair of resilient members 116, the latter being secured to subbase member 12 in a suitable manner such as by rivets 117 and extending outwardly from the subbase to form resilient catches as illustrated in Figs. 2 and 3. The side portions 118 of the cover are preferably of molded resinous material while the center strip 119 extending the full length of the cover and curving inwardly at both ends may be of brass. Brass strip 119 may be conveniently secured to the plastic portion 118 of the cover by a pair of inwardly disposed angular portions 120 at the top and bottom, this construction permitting the brass strip to be assembled merely by snapping it into place on the plastic portion of the cover. A plurality of openings 121 are provided in the upper and lower end portions of strip 119 to provide for the circulation of air over the switch mechanism.

Before the strip 119 is assembled with the remainder of the cover a thermometer 122 is secured thereto in a central position, the thermometer being supported by a suitable support member 123 which is part of the molded case. A vertical slot 124 is provided in member 119 on the front of the device to enable the thermometer to be read, while suitable indicia are provided along the side of the slot for use in determining the height of the fluid in the thermometer.

The improved bimetal unit mounting structure of this invention enables the thermostatic bimetal operating element 69 to be formed of a bimetallic piece of material which is substantially straight at normal temperatures. Such a straight piece of bimetal maintains a higher degree of accuracy and sensitivity of control as it is never subjected to internal strains which become released in service or upon aging as do bimetal operating elements formed, for example, in a spiral, or U-shape. Moreover, the mounting of the normally straight bimetal element 69 in substantially parallel spaced-apart relation with the subbase 11 enables a free flow of room air through the various ventilating openings in the top and bottom of the removable cover 111 directly over the surfaces of the bimetal element as indicated in Figs. 2 and 3. This enables the normally straight bimetal element 69 to respond readily to slight changes in temperature of the ambient room air. The bimetal element 69 is positioned within the enclosing case at the maximum distance from subbase 11, and the base in turn is spaced away from the wall by mounting bosses 19 and 21; this serves to reduce the wall temperature effect upon the thermostat due to the intervening air spaces and thereby aids in making the bimetal element accurately responsive to room air temperature.

The cam assembly at the upper end of the device which provides means for adjusting the temperature setting of the thermostatic switch has two calibrating means. The first of these, which is intended primarily for factory calibration, is provided by set screw 18. By turning this screw the position of the upper end of bimetal 69 relative to the helical cam surface 50

can be adjusted, it being recalled that spring member 70 is biased so that the inner end of screw 78 always remains in contact with helical cam surface 50. In calibrating the thermostatic switch, if it is desired that bimetal 69 move contact 80 to the closed contacts position at a lower temperature, set screw 78 is turned so that the upper end of bimetal 69 is moved closer to cam surface 50; this will cause bimetal 69 to operate at a lower temperature to close contacts 80, 88 at the lower end of the bimetal, while turning set screw 78 so that the distance between bimetal 69 and helical cam surface 50 is increased has the opposite effect. Additional calibrating means for the cam mechanism are provided by the rotatable connection between cam member 37 and dial 47 which permits one to be rotated with respect to the other, it being understood that there is sufficient friction between them that the two normally turn together when dial 47 is turned. The second calibrating arrangement is provided primarily for the benefit of householders who may feel that the factory calibration is not accurate due to varying conditions in individual heating and air conditioning installations and the like. If, for example, the householder feels uncomfortable at a particular temperature, such as 72°, which he feels should be maintained, he can slip the cam member 37 on the dial 47 so that the dial still reads 72° but the thermostat actually holds a temperature above or below this value, depending on the amount of relative rotation of member 37 with respect to dial 47.

The differential of the thermostatic switch, that is, the difference between the temperature at which bimetal 69 closes the contacts 80, 88 and the temperature at which it opens them again is adjustable by moving member 94. This turns screw 92 in and out and decreases and increases the spacing of spring 90 with respect to the subbase. This in turn adjusts the spacing between armature 81 and magnet 82 in the closed contacts position, it being understood that armature never actually engages either magnet 82 or non-magnetic supporting portions 85. The smaller this spacing is made, the greater the differential becomes because a greater force is required to pull the armature out of the attractive field of the magnet. Conversely, as the spacing between armature 81 and magnet 82 is increased the differential decreases. In a typical apparatus, the differential may be adjustable from 2 to 4° F., although the differential may be readily made more or less by suitably proportioning the elements of the differential mechanism in order to conform to the requirements of a particular installation. As mentioned previously, the indicia 99 in co-operation with pointer 98 indicate the differential setting of the device.

In operation, one side of an electrical circuit which is to be opened and closed by the thermostatic switch 10 is connected to the lefthand terminal 101 and thence through resistor 109 to lefthand terminal 23. A jumper may be substituted for resistor 109, if desired. From lefthand terminal 23 the electrical circuit is continued through conductive member 30 including portions 32, 34 and 35 in this order. Portion 35 is connected to spring 70 at junction 75 from which the electrical circuit continues through supporting arm 76 and then through screws 126 and bimetal 69 to movable contact 80. When contacts 80 and 88 are in engagement the circuit is completed through fixed contact 88, spring 89,

rivets 71, portions 39, 38 and 36 of conductive member 31 and thence to righthand terminal 23. The other side of the external circuit is connected to righthand terminal 23. When the ambient temperature is below a predetermined value dependent upon the setting of the cam adjusting mechanism and the differential adjusting mechanism, bimetal 69 springs inwardly and causes movable contact 80 to engage fixed contact 88. This may, for example, energize an electrical control circuit which initiates the operation of a heating apparatus to increase the room temperature. Then when the temperature increases to a second higher predetermined value dependent upon the setting of the differential mechanism, bimetal 69 swings outwardly, opening contacts 80 and 88 and de-energizing the heater circuit.

Thus, it will be seen that I have provided a thermostatic device constructed of a relatively few parts which are simple and readily formed and which may be assembled to provide a rugged thermostat which is not susceptible to damage or to false operation due to shock or vibration. The thermostat is also easy to install, it being necessary only to provide two screws for fastening subbase 11 to a wall or other supporting member by means of bosses 19 and 21 while the base, the operating mechanism and the cover are removed. If desired, a fiberboard or other shield, having holes for the electrical leads, may be placed between the subbase and the wall to prevent drafts due to the holes cut in the wall for the leads from affecting the bimetal element. Terminals 23 and 101 are already in place on the subbase, and resistors 109 and 110 may also be in place during this operation. Then after connections to the external control wires have been made to terminals 23 and 101 by means of screws 28 and 104 respectively, the base and operating mechanism assembly is put in place merely by loosening screws 33 and 125 sufficiently to insert the corresponding recesses in portions 32 and 36 respectively beneath the screw heads, after which the screws are tightened to hold the base with the operating mechanism mounted thereon rigidly in place. Thereafter, it is necessary only to put the cover in place by hooking projection portion 113 over projection 114 at the top of the subbase and springing projections 115 on the cover into place in engagement with members 116 at the bottom of the subbase.

While I have illustrated and described my invention in a form useful primarily as a thermostatic switch for heating or cooling service, it will be understood that it may readily be adapted for use in controlling other conditions. For example, it may be converted from a thermostat as shown to a humidostat merely by replacing the bimetal element 69 of the thermostat with a special humidity responsive operating element. Such a humidity responsive operating element consists of a relatively thin metal strip which is united throughout its length to a strip of suitable humidity responsive material such as wood, cellulose or the like. It will be understood that this and other modifications may be made by those skilled in the art. Therefore, it should be understood that my invention is not limited to the preferred embodiment which I have illustrated and described but covers all modifications which fall within the spirit and scope of the following claims.

What I claim as new and desire to secure by Letters Patent of the United States is:

1. A condition responsive switch comprising a

flatly disposed elongated subbase at least a portion of which is made of electrical insulating material, a pair of conductive terminal members secured to said insulating portion on one surface of said subbase, an elongated base secured to said subbase by means of said terminal members and supported thereby, said base being positioned in spaced-apart approximately co-extensive relation with said subbase, said base comprising a first elongated conductive member connected to one terminal member and a second shorter conductive member connected to the other terminal, said two conductive members jointly supporting near one end of said device a flatly disposed insulating member having a circular opening therein, a circular cam member having a helical cam surface rotatably positioned in said opening, a circular adjusting dial positioned in concentric interfitting jointly rotatable relation with said cam member, said cam member being selectively rotatable with respect to said dial to provide a first calibrating means, a conductive spring member secured centrally of said base on said first conductive member but insulated therefrom, means connecting said second conductive member electrically to said spring, a conductive supporting arm connected to said spring and extending longitudinally adjacent said helical cam surface, said spring biasing said arm toward said cam surface, a set screw extending through said arm and engaging said cam surface for adjusting the distance between said arm and cam surface to provide a second calibrating means, an elongated conductive condition responsive element having one end secured to said arm adjacent said cam member and extending in substantially parallel spaced-apart relation with said subbase and approximately coextensive with the intervening base, a movable contact positioned near the opposite end of said condition responsive element, and a cooperative fixed contact carried by said base and connected electrically to said first conductive member, said condition responsive element moving said movable contact into and out of engagement with said fixed contact in response to predetermined changes in said condition to make and break an electrical circuit between said terminal members through said contacts.

2. A thermostatic switch comprising a flatly disposed elongated subbase at least a portion of which is made of electrically insulating material, a pair of conductive terminal members secured to said insulating portion adjacent opposite sides of one surface of said subbase, an elongated base secured to and supported by said terminal members and positioned in spaced apart approximately coextensive relation with said subbase, said base comprising a first elongated conductive member connected to one terminal member and extending substantially the full length of said base and a second shorter conductive member connected to the other terminal, said two conductive members jointly supporting near one end of said switch a flatly disposed insulating member having a circular opening therein, a circular cam member having a helical cam surface rotatably positioned in said opening, a circular dial positioned in concentric interfitting jointly rotatable relation with said cam member, said cam member being selectively rotatable with respect to said dial, a conductive leaf spring member secured centrally of said first conductive member and insulated therefrom, means electrically connecting said second conductive member and said spring, a conductive supporting arm connected to said

spring and extending longitudinally adjacent said helical cam surface, said spring biasing said arm toward said cam surface, a set screw extending through said arm and engaging said cam surface for adjusting the distance therebetween to provide a calibration means for said switch, an elongated bimetal element having one end secured to said arm adjacent said cam member and extending in substantially parallel spaced apart relation with said subbase and approximately coextensive with the intervening base, an armature secured to the opposite end of said bimetal element, a permanent magnet secured to said base near the opposite end thereof, said permanent magnet cooperating with said armature to provide snap action of said bimetal toward and away from said base responsive respectively to a decrease in temperature below a predetermined value and an increase in temperature above a higher predetermined value, a movable contact carried by said bimetal, a relatively fixed contact carried by a relatively weak cantilever spring member supported centrally of said first conductive member and connected electrically thereto, said cantilever spring member being biased toward said bimetal, a second relatively strong cantilever spring member secured between said first cantilever spring member and said base in approximately parallel relation with said first cantilever spring, said second cantilever spring being biased away from said bimetal and having a projection thereon embracing said first cantilever spring and confining said first spring to a small movement between said embracing projection and said second spring, said bimetal forcing said first cantilever spring into engagement with said second cantilever spring when it moves toward said base into the contacts closed position, said first cantilever spring following said bimetal for a short distance until stopped by said projection thus causing said contacts to open when said bimetal moves away from said base, and adjustable stop means supported on said base for adjusting the position of said second cantilever spring to vary the gap between said armature and said permanent magnet when said contacts are engaged in order to vary the difference between said predetermined temperatures.

3. A thermostatic switch comprising a subbase formed by a flatly disposed elongated metal subbase member having at least two mounting bosses projecting from one surface thereof and an insulating subbase member secured to the other surface of said metal subbase member, a pair of conductive terminal members secured to said insulating subbase member adjacent opposite sides thereof on the surface away from said metal subbase member, an elongated base assembly secured to and supported by said terminal members and positioned in spaced apart approximately coextensive relation with said subbase, said base comprising a first elongated conductive member connected to one terminal member and extending substantially the full length of said base, said first conductive member having 3 offset portions located progressively farther away from said subbase beginning at one end of said switch, the intermediate offset portion of said first conductive member being approximately centrally located, a second shorter conductive member connected to the other terminal having a flatly disposed portion near said first end of said switch which is coplanar with the first offset portion of said first conductive member but isolated electrically therefrom, a

flatly disposed insulating member jointly supported by said coplanar portions of said conductive members on the under surface of said base between said conductive members and said subbase, said first conductive member having a circular opening in said first offset portion thereof and said flatly disposed insulating member having a circular opening coaxial therewith, a circular frictional spacing member positioned in coaxial relation with said openings on the outer surface of said first offset portion opposite said flatly disposed insulating member, a flat circular dial having a circular opening therein coaxially positioned on the outer surface of said spacing member, a circular cam member provided with a helical cam surface rotatably secured in said four coaxial openings whereby a temperature adjusting and calibrating assembly is formed, said dial and said cam member being jointly rotatable with respect to said first offset portion through a portion of a complete rotation to provide for the temperature adjustment of said switch, and said dial and said cam member being selectively rotatable with respect to each other through a portion of a complete rotation to provide a first calibrating means, indicia on said dial, a pointer secured to said flatly disposed insulating member and cooperating with said indicia to indicate the setting of said switch, a conductive spring member secured to said intermediate offset portion of said first conductive member and insulated therefrom, means electrically connecting said second conductive member to said spring, a conductive supporting arm connected to said spring and extending longitudinally adjacent said helical cam surface, said spring biasing said arm toward said cam surface, a screw extending through said arm and engaging said cam surface for adjusting the distance between said arm and said cam surface whereby a second calibrating means is provided for said switch, an elongated bimetal element having one end secured to said arm adjacent said cam member and extending in substantially parallel spaced apart relation with said subbase and approximately coextensive with the intervening base, a movable contact carried by said bimetal near the opposite end thereof, a relatively fixed contact carried by a first relatively weak cantilever spring member supported on said intermediate offset portion of said first conductive member and connected electrically thereto, said first cantilever spring member being approximately parallel to the

third offset portion of said first conductive member and biased toward said bimetal, a second relatively strong cantilever spring member supported in superimposed relation on said intermediate offset portion between said first cantilever spring member and said base in substantially parallel relation with both, said second cantilever spring being biased away from said bimetal and having a projection thereon embracing said first cantilever spring and coining said first spring to a small movement between said projection and said second cantilever spring, said bimetal forcing said first cantilever spring into engagement with said second cantilever spring when it moves toward said base into the contacts closed position, said first cantilever spring following said bimetal for a short distance when said bimetal moves away from said base until stopped by said projection on said second cantilever spring which causes said contacts to open, adjustable stop means supported on said third offset portion of said base for adjusting the position of said second cantilever spring toward and away from said third offset portion to vary the travel of said bimetal toward said base in the contacts closed position, an armature secured to the end of said bimetal element adjacent said movable contact, a permanent magnet secured to said third offset portion of said first conductive member in spaced apart relation with said armature, said permanent magnet cooperating with said armature to provide snap action of said bimetal toward and away from said base in closing and opening said contacts in response respectively to a decrease in temperature below a predetermined value and an increase in temperature above a higher predetermined value, the position of said adjustable stop means relative to said third offset portion determining the difference between said predetermined temperatures.

RALPH M. MANNING.
